UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A PLATE OR SIMILAR ARTICLE OF MANUFACTURE.

Application filed April 4, 1923. Serial No. 5,691. Term of patent 3½ years.

To all whom it may concern:

Be it known that I, MARTHA HALOWELL CONNOR, a citizen of the United States, residing in the city of Baltimore, State of Maryland, have invented a new, original, and ornamental Design for a Plate or Similar Article of Manufacture, of which the following is a specification, reference being had to the accompanying drawing, forming a part thereof, wherein—

What I claim is:

The ornamental design for a plate or similar article of manufacture as shown and described.

MARTHA HALOWELL CONNOR.
